FUR STRETCHING FRAME

Filed Jan. 7, 1931

UNITED STATES PATENT OFFICE

1,932,167

FUR STRETCHING MACHINE

Henry J. Weigand, Canton, and Paul V. Scheetz,
Massillon, Ohio

Application January 7, 1931. Serial No. 507,136

12 Claims. (Cl. 149—21)

The invention relates to frames for stretching fur, and more particularly to a frame especially designed for stretching the skins of fox, mink and other small animals for use as fur scarfs.

Such skins are whole except for an opening adjacent to the back legs, and the skin of the back legs is usually slit longitudinally. The ordinary method of stretching these skins is to first soak the skin in water until it is sufficiently soft and pliable, after which a block of cork or the like is inserted into the nose and the skin is placed over a board and stretched thereon by hand.

Such practice does not permit of stretching the skin either longitudinally or transversely to the maximum; provides no means of stretching the neck transversely; usually stretches the skin at each side to such an extent that the fur is too thin at these points where the finished scarf gets the greatest wear; and further, no means is provided for stretching the back legs.

The object of the present improvement is to provide a fur stretching frame which will overcome the objections and difficulties encountered under present practice by providing means for stretching skins to the maximum extent both longitudinally and transversely, as well as for stretching the neck portion and back legs of the skin.

Another object is to provide means for so stretching the skin that the fur will remain the thickest along each side of the skin, thus not only enhancing the appearance of the finished scarf but providing for the heaviest fur at the points where the scarf receives the greatest wear.

The above and other objects which will be obvious from an inspection of the drawing, or which will be pointed out in the following detail description of the invention, may be attained by forming the improved stretching frame of a pair of spaced, parallel frame members, each being substantially square in cross section and a portion of a head block being carried upon one end of each frame member, means being provided for separating the frame members and maintaining their parallel relation to each other.

A pair of oppositely tapered neck stretching blocks is slidably mounted upon the frame members and arranged to be moved longitudinally thereon to any desired or necessary position. There is also a pair of leg stretching blocks slidably mounted upon the frame members for stretching the back legs, and arranged to be moved to the desired position thereon to stretch the fur longitudinally, means being provided for

locking the leg blocks in any adjusted position with relation to the frame members.

An embodiment of the invention is illustrated in the accompanying drawing, in which

Figure 1 is a plan view of the improved fur stretching frame;

Fig. 2, an edge elevation of the same;

Fig. 3, an end view of the frame showing the rear end thereof;

Fig. 4, a similar view of the head end of the frame;

Fig. 5, a transverse section on an enlarged scale, taken as on the line 5—5, Fig. 1; and

Fig. 6, a similar section on the line 6—6, Fig. 1.

Similar numerals refer to similar parts throughout the drawing.

The improved fur stretching frame includes a pair of parallel frame members 10 of any suitable length, depending upon the kind of animal skin to be stretched. Each of these frame members is preferably formed of wood and is substantially square or rectangular in cross section.

An adjusting rod 11 is located between these parallel frame members, being connected to the frame members at intervals by the pairs of toggle links 12. The rear end portion of this rod is screw threaded as at 13, and is located through a suitable opening in the channel-shaped guide plate 14, formed of sheet metal, or the like, and arranged to receive the rear ends of the frame members 10, a nut 14a being located upon the threaded end of the rod.

The front or head end of each frame member 10 is provided with a head block 15, which may be formed of wood, sheet metal or other suitable material, and which is so shaped as to properly form the back portion of the head of the skin and prevent the same from being depressed or caved-in when stretched.

In order to prevent a hollow or reduced appearance in the neck portion of the skin, and to properly stretch the same to the desired width, a pair of oppositely tapered, or curved, neck blocks 16 is slidably mounted upon the frame members.

For the purpose of permitting these neck blocks to move transversely with the frame members 10, sheet metal plates 17 are fixed to opposite sides of one neck block, as by tacks 18, and slidably mounted in the channel edge portions of similar plates 19, attached to the other neck block as by the tacks 20.

The plates 17 may be provided with the angular tongues 21 adapted to engage the inner edge of the corresponding frame member 10, so

as to prevent accidental displacement of the corresponding neck block.

In order to adjust the neck blocks longitudinally upon the frame members, a rod or wire 22 5 may be connected to the neck blocks and extend through a longitudinal groove 22a in one of the frame members, to the rear end of the frame, having the angular end portion 23 by means of which the neck blocks may be manually adjusted after the skin has been placed over the frame.

A pair of leg blocks 24 is slidably mounted upon the frame members, each block having its forward end tapered as at 25 to permit the open 15 rear end portion of the skin to be pulled there-over.

The side edges of the leg blocks are preferably rounded as shown at 26, and the hind legs of the skin are arranged to be stretched over the same.

20 For the purpose of stretching the legs over these blocks, a series of pins 27 is mounted in the upper side of each leg block, and a similar row of pins 27a is mounted in the under side of each block. 25 Each of the leg blocks is slidably mounted upon the frame members by means of plates 28 and 29 similar to the plates 17 and 19 upon the neck blocks. In order to hold the leg blocks in adjusted position upon the frame members, each 30 frame member is provided with a series of apertures 30, and a similar aperture 31 is provided in each leg block, for the reception of a double hook or staple 32.

In operating the frame to stretch a fur, the 35 skin is first soaked until it is in proper condition for stretching. A block of cork, or the like, is then placed in the nose portion of the skin and the head end of the frame is inserted into the open rear end of the skin, the head blocks 15 being placed in contact with the nose block.

The hind legs are stretched over the leg blocks and pinned thereto by the pins 27 and 27a, and these leg blocks are pulled rearward upon the frame members to stretch the entire skin longitudinally. When the leg blocks are moved to the 45 desired position, the double hooks or staples 32 are inserted into the proper apertures 30 and 31, holding the leg blocks in this position.

The neck blocks 16 may be longitudinally adjusted to the desired position by means of the 50 rod or wire 22, the angular end 23 thereof being accessible for manual operation after the skin has been placed over the frame.

Transverse stretching of the skin is obtained by turning up the nut 14a upon the threaded portion of the rod 11, which through the toggle 55 links 12 separates the frame members 10, expanding the entire frame and stretching the skin transversely.

By providing substantially sharp corners upon the outer sides of the frame members 10, it will be seen that the skin will be held in normal condition between these corners over each outer side of the frame members, thus preventing undue 65 stretching of the side edge portions of the skin and leaving the fur at these points in its natural heavy condition so as to withstand the wear to which it is subjected in use.

In order to further stretch the legs of the skin 70 transversely, a wedge of any suitable construction may be driven into the end of the slot 34 in each of the leg blocks 24, spreading the blocks, while the legs are held by the pins 27 and 27a.

We claim:

75 1. A fur stretching frame including a pair of parallel frame members each frame member hav-

ing a flat outer surface and substantially sharp corner edges, a rod located between the frame members, toggle links connecting the rod to the frame members, a plate contacting with one end of each frame member, the adjacent end of the 80 rod being screw threaded and located through the plate, and a nut upon the threaded end of the rod.

2. A fur stretching frame including a pair of parallel frame members each having a flat outer 85 surface and substantially sharp corner edges, a rod located between the frame members, toggle links connecting the rod to the frame members, a channel member receiving one end of each frame member, the adjacent end of the rod being screw threaded 90 and located through the channel member, and a nut upon the threaded end of the rod.

3. A fur stretching frame including a pair of parallel frame members, a rod located between 95 the frame members, toggle links connecting the rod to the frame members, a plate contacting with one end of each frame member, the adjacent end of the rod being screw threaded and located through the plate, a nut upon the threaded end of the 100 rod, and a head block carried by the opposite end of each frame member.

4. A fur stretching frame including a pair of parallel frame members, a rod located between the frame members, toggle links connecting the 105 rod to the frame members, a channel member receiving one end of each frame member, the adjacent end of the rod being screw threaded and located through the channel member, a nut upon the threaded end of the rod, and a head block 110 carried by the opposite end of each frame member.

5. A fur stretching frame including a pair of parallel frame members, a rod located between the frame members, toggle links connecting the 115 rod to the frame members, a plate contacting with one end of each frame member, the adjacent end of the rod being screw threaded and located through the plate, a nut upon the threaded end of the 120 rod, and means upon the frame members for stretching the neck portion of a fur.

6. A fur stretching frame including a pair of parallel frame members, a rod located between the frame members, toggle links connecting the 125 rod to the frame members, a channel member receiving one end of each frame member, the adjacent end of the rod being screw threaded and located through the channel member, a nut upon the threaded end of the rod, and means 130 upon the frame members for stretching the neck portion of a fur.

7. A fur stretching frame including a pair of parallel frame members, a rod located between the frame members, toggle links connecting the 135 rod to the frame members, a plate contacting with one end of each frame member, the adjacent end of the rod being screw threaded and located through the plate, a nut upon the threaded end of the 140 rod, and a pair of neck stretching blocks slidably mounted upon the frame members.

8. A fur stretching frame including a pair of parallel frame members, a rod located between the frame members, toggle links connecting the rod to the frame members, a channel member receiving one end of each frame member, the adjacent end of the rod being screw threaded and located through the channel member, a nut upon the threaded end of the rod, and a pair of neck stretching blocks 145 slidably mounted upon the frame members.

9. A fur stretching frame including a pair of parallel frame members, a rod located between the frame members, toggle links connecting the rod to the frame members, a plate contacting with one end of each frame member, the adjacent end of the rod being screw threaded and located through the plate, a nut upon the threaded end of the rod, a pair of leg stretching blocks slidably mounted upon the frame members, and means for holding said leg stretching blocks in adjusted position.

10. A fur stretching frame including a pair of parallel frame members, a rod located between the frame members, toggle links connecting the rod to the frame members, a plate contacting with one end of each frame member, the adjacent end of the rod being screw threaded and located through the plate, a nut upon the threaded end of the rod, a pair of leg stretching blocks slidably mounted upon the frame members, and means for holding said leg stretching blocks in adjusted position, each leg stretching block being longitudinally slotted and adapted to be expanded by a wedge.

11. A fur stretching frame including a pair of parallel frame members, a rod located between the frame members, toggle links connecting the rod to the frame members, a plate contacting with one end of each frame member, the adjacent end of the rod being screw threaded and located through the plate, and a nut upon the threaded end of the rod, each frame member being substantially rectangular in cross section and having sharp outer corners.

12. A fur stretching frame including a pair of parallel frame members, a rod located between the frame members, toggle links connecting the rod to the frame members, a channel member receiving one end of each frame member, the adjacent end of the rod being screw threaded and located through the channel member, and a nut upon the threaded end of the rod, each frame member being substantially rectangular in cross section and having sharp outer corners.
